UNITED STATES PATENT OFFICE.

JOSEPH B. MERIAM, OF CLEVELAND, OHIO.

FLUID-INDICATOR.

1,055,063.

Specification of Letters Patent. Patented Mar. 4, 1913.

Application filed February 7, 1911. Serial No. 607,203.

To all whom it may concern:

Be it known that I, JOSEPH B. MERIAM, a citizen of the United States, residing at Cleveland, in the county of Cuyahoga and State of Ohio, have invented a new and useful Improvement in Fluid-Indicators, of which the following is a full, clear, and exact description, reference being had to the accompanying drawings.

10 This invention relates to gages or indicators for showing the amount of fluid passing through an orifice. Taking an orifice of a given size and passing a fluid therethrough, the amount of such fluid passing is dependent upon the differences in pressure of the fluid on the opposite sides of the member containing the orifice. In my invention I utilize this principle in a mechanism having a transparent tube, preferably 20 a U-tube, the ends of which are connected to chambers containing different colored liquids, the chambers being separated from each other except as they are connected through the tube, and each of said chambers 25 being connected with the passage for fluid on the respective sides of the member containing the orifice.

In the accompanying drawing, which shows one embodiment of my invention, 30 Figure 1 is a front elevation of my invention shown in somewhat diagrammatic form, part of the connecting pipes being broken away; Fig. 2 is a sectional view taken on the line 2—2 of Fig. 1; Fig. 3 is 35 a sectional view taken on the line 3—3 of Fig. 1, and Fig. 4 is a view showing the disk or member having the orifice therein.

Taking up a fuller description of the invention by the use of the reference characters appearing on the drawings, 1 and 2 represent two hemispherical castings, the same being so assembled as to form a spherical casing, said castings being held together in any suitable manner so as to be fluid tight. 45 Between the said parts 1 and 2 I place a disk 3, the same being shown in detail in Fig. 4, the disk being clamped about its edges so that no fluid can pass from one side of the disk to the other except through an orifice 4 therein, said orifice being preferably at the center of the disk, as shown. 50 Leading into the spherical casing on one side of the disk is an inlet pipe 5 which carries the fluid that is to be measured or

gaged, and a similar pipe 6 leads outwardly 55 from said casing to the engine or other device to which the fluid is supplied. This fluid must, of course, pass through the orifice 4; and the purpose of my invention is to show by a visual indicator the amount of 60 the fluid thus passing. To that end, I attach to the casing members 1 and 2 pipes 7 and 8 respectively, and I connect the opposite ends of said pipes to a containing vessel 9, said vessel being divided by a partition 10 into two chambers or compartments 11 and 12, the pipes 7 and 8 communicating with the chambers 11 and 12 respectively. These 65 chambers are connected together exteriorly by a glass tube, the same being bent into a 70 U-shape and having the legs 13 and 13^a connected with the respective chambers 11 and 12. The chambers are partially filled with 75 liquids, as indicated in Fig. 2, the liquids of the two chambers being of different character so that they will not mix, although they should be of the same or approximately of the same specific gravity. Furthermore, the 80 liquid in one of the chambers should be colored, and Fig. 2 is intended to show colored liquid in chamber 11. From this construction it results that the liquids in the chambers will fill the U-tube and that the meeting point of the liquids in the tube will be 85 clearly marked by the difference in the colors of the liquids, such meeting point being indicated at 14. The position of this point will vary with the quantity of fluid 90 passing through the orifice 4 or with the pressures on the opposite sides of said orifice. Assuming that there is no fluid present in the pipes 5 or 6 or in the casing for the disk, then the meeting point 14 will be located at some point along a scale 15. If a fluid be introduced through the pipe 5, 95 then the pressure on the left hand side of the disk will exceed the pressure on the right hand side thereof, and the fluid will pass through the orifice from the left to the right. At the same time, this difference in 100 pressure exists in the chambers 11 and 12, and the point 14 moves downwardly in the tube and appears opposite another point on the scale. This scale may be graduated to indicate quantities or volumes of fluid passing 105 through the orifice in a given time, or it may be graduated so as to indicate differences of pressure existing on opposite sides of the

disk, or to indicate the velocity of the fluid passing through the orifice. In any case, if the quantity or volume of fluid cannot be read directly from the scale, it may be readily computed therefrom.

For varying the effective size of the orifice 4, I may employ a valve having a conical end 16 within the spherical casing and a stem 17 that is screw-threaded into the casting member 1. By turning this stem, the conical part 16 of the valve may be screwed into or out of the orifice, thereby changing the size of the latter as may be desired.

For preventing a too sudden change of the liquids in the U-tube, a valve may be interposed at practically any point in either of the pipes 7 or 8. In Fig. 2 I have shown such a valve at 18, the same being preferably of the type known as a needle valve. I also prefer to place valves in both the pipes 7 and 8 for the purpose of closing these pipes in case it should be desired to do so, as while filling or otherwise changing the liquids in the chambers 11 and 12, such valves being shown at 19 and 20.

For the purpose of protecting the U-tube against injury, I surround the same with shields 21 and 22, which shields are secured to the vessel 9 in any suitable manner. In Fig. 3 I have shown a section through these protecting shields, from which it will be seen that they are shaped somewhat like channel-irons so as to completely inclose the tube except a portion of the leg 13, and this portion of the tube is contained within a recess in the front of the shields so as to be protected from injury. The graduated scale 15, heretofore referred to, is preferably impressed upon one of these protecting shields, Fig. 1 showing the same on shield 22.

In case it should be desired to fix or establish any particular point on the scale, and to reckon from that point the volume or velocity of the fluids passing through the orifice, or the differences in pressure on opposite sides of the orifice, this may be done by a pointer 23 which I mount upon the shield 21, or upon that shield that is opposite the scale 15. This pointer may be moved to any position along the scale and may be held there by a set screw 24, or by any other suitable fastening means.

In order to introduce the liquids to the chambers 11 and 12, the upper walls of these chambers are provided with threaded openings, which are normally closed by plugs 25.

While my invention may be employed in many different relations, and the following claims are intended to cover the same however employed, I contemplate the use of the same chiefly in connection with internal combustion engines, the gases for operating which are passed through the pipes 5 and 6 and through the orifice.

Having thus described my invention what I claim as new and desire to secure by Letters-Patent is:

1. In a device of the character described, the combination with a casing having a passage for fluids therethrough, of a partition through said casing, said partition having an orifice therein through which the fluids must pass, a valve controlling the aperture of the orifice, a vessel having a partition therein so as to be divided into a pair of chambers, means connecting each of said chambers with the said casing, the connections for the respective chambers being on opposite sides of the partition in the casing, a transparent U-tube having its ends connected with the respective chambers through which tube the chambers communicate with each other, and liquids of different colors contained within the respective chambers, said liquids meeting within the said U-tube.

2. In a device of the character described, the combination with a member having a passage for fluids therethrough, of a disk extending across the passage in the member and forming a partition therein, said disk being provided with an orifice through which the fluids pass, a valve controlling the aperture of the orifice, a vessel having a pair of chambers therein, a pipe for each chamber, said pipes connecting the respective chambers with the said member on the opposite sides of the disk, a U-tube having its ends connected to the said vessel and communicating with the respective chambers therein, liquids contained within the said chambers and within the said U-tube, said liquids having different colors so that the point of meeting of the liquids in the U-tube is visible, and an index scale adjacent the said tube, as and for the purpose specified.

3. In a device of the character described, the combination with a pair of hemispherical castings so assembled together as to form a hollow spherical member, of a disk between the said castings, said disk forming a partition across the member and the disk having an orifice therethrough, a valve connected with one of the said castings and having a conical end that is adapted to enter the orifice and to vary the effective size thereof, a vessel having a pair of chambers therein, pipes connecting the respective chambers with the said member on opposite sides of the disk, a U-tube having its ends connected with the respective chambers and a protecting shield extending from the said vessel about the said tube to protect the same from injury.

4. In a device of the character described, the combination with a member having a passage for fluids therethrough, of a disk extending across said passage, said disk having an orifice through which the liquids

pass, a valve controlling the aperture of the orifice, a vessel having a pair of chambers therein, pipes connecting the respective chambers with the member on opposite sides of the disk, a U-tube having its respective ends communicating with the said chambers, fluids of different colors within the respective chambers and within the said tube, said fluids meeting within the tube, said fluids meeting within the tube, and a protecting shield for the said U-tube said shield having a graduated scale marked thereon, as and for the purpose specified.

5. In a device of the character described, the combination with a member having a passage for fluids therethrough, of a disk extending across said passage, said disk having an orifice through which the fluids pass, a vessel having a pair of chambers therein, pipes connecting the respective chambers with the member on opposite sides of the disk, a U-tube having its respective ends connected with the said chambers, a pair of channeled members connected with the vessel, said members inclosing one leg 5 of the said tube and containing the other leg of the tube within a recess of the channel members, an index scale on one of said channel members and an index pointer adjustably secured to the other channel member, as and for the purpose specified.

6. In a device of the character described, the combination with a member having a passage for fluids therethrough, of a disk extending across said passage, said disk having an orifice therein through which the fluids pass, a valve controlling the aperture of the orifice, a vessel having a pair of chambers therein, pipes connecting the respective chambers with the member on opposite sides 10 of the disk, a U-tube having its ends communicating with the respective chambers, liquids of different colors within the respective chambers and within the said tube, and a valve in each of the pipes connecting the vessel with the said member, as and for the purpose specified.

7. In a device of the character described, the combination with a member having a passage for fluids therethrough, of a disk 15 extending across said passage, said disk

having an orifice therein through which the fluids pass, a vessel having a pair of chambers therein, pipes connecting the respective chambers with the member on opposite sides of the disk, a U-tube having its ends communicating with the respective chambers, liquids of different colors within the respective chambers and within the said tube, a valve in each of the pipes connecting the vessel with the said member, and another 55 valve for regulating the size of the orifice in the disk, as and for the purpose specified.

8. In a device of the character described, the combination with a member having a passage for fluids therethrough, of a disk 60 extending across said passage, said disk having an orifice therein, a valve controlling the aperture of the orifice, a vessel having a pair of chambers, pipes connecting the respective chambers with the member on opposite sides of the disk, a U-tube having its ends communicating with the respective chambers, liquids of different colors within the said chambers and within the tube, and a valve located within one of the pipes between the vessel and the member, said valve being adapted to regulate the flow of fluid 65 between the member and the vessel.

9. In a device of the character described, the combination with a member having a 70 passage for fluids therethrough, of a disk extending across said passage, said disk having an orifice through which the fluids pass, a vessel having a pair of chambers therein, pipes connecting the respective chambers 75 with the member on opposite sides of the disk, a U-tube having its respective ends connected with the said chambers, and a pair of channeled members connected with the vessel, said members inclosing one leg of the said tube and containing the other leg of the tube within a recess of the channeled members, as and for the purpose specified.

In testimony whereof, I hereunto affix my 80 signature in the presence of two witnesses.

JOSEPH B. MERIAM.
